US0D1110299S

(12) **United States Design Patent** (10) **Patent No.:** **US D1,110,299 S**
(45) **Date of Patent:** **** Jan. 27, 2026**

(54) **PORTABLE DISPLAY DEVICE**

(71) Applicants: **LG Display Co., Ltd.**, Seoul (KR);
**SOOKMYUNG WOMEN'S
UNIVERSITY
INDUSTRY-ACADEMIC
COOPERATION FOUNDATION**,
Seoul (KR)

(72) Inventors: **Heung Ryeol Kim**, Seoul (KR); **Chang Kuk You**, Seoul (KR)

(73) Assignees: **LG DISPLAY CO., LTD.**, Seoul (KR);
**SOOKMYUNG WOMEN'S
UNIVERSITY
INDUSTRY-ACADEMIC
COOPERATION FOUNDATION**,
Seoul (KR)

(**) Term: **15 Years**

(21) Appl. No.: **29/926,387**

(22) Filed: **Jan. 30, 2024**

(30) **Foreign Application Priority Data**

Jul. 31, 2023 (KR) 30-2023-0029784

(51) LOC (15) Cl. **14-02**

(57) **CLAIM**

The ornamental design for a portable display device as shown and described.

DESCRIPTION

FIG. 1 is a front, right, top perspective view of a portable display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the portable display device that form no part of the claimed design.

1 Claim, 7 Drawing Sheets
